F. P. SHEK

LOCK

Filed Nov. 29, 1922

Inventor

Frazer P. Shek

By his Attorney
Frank Freeman

UNITED STATES PATENT OFFICE.

FRANK P. SHEK, OF BROOKLYN, NEW YORK.

LOCK.

Application filed November 29, 1922. Serial No. 603,974.

To all whom it may concern:

Be it known that I, FRANK P. SHEK, a citizen of the United States, residing at Brooklyn, county of Kings, city of New York, and State of New York, have invented new and useful Improvements in Locks, of which the following is a full, clear, and exact specification.

My invention relates to locks and refers particularly to locks having double shackle engaging means.

My invention is directed to a lock having the locking means intermediate of two shackle loops, each, or both, of which are capable of being opened and closed by a sliding movement of the locking mechanism along the shackle rods.

In a device of my invention described in United States Patent No. 1,452,393, dated April 17, 1923, I have described a lock of the same general character in which the shackle is formed of one rod bent to the desired form, in which the opening between the spaced ends of the shackle rod is bridged by the container carrying the locking mechanism when the device is in locked position.

In the device of that application, it is necessary to move the container along the shackle for a distance at least equal to the opening in the shackle necessary for the admission of the article which it is desired to maintain in a locked position with regard to the lock. This requires a shackle of considerable length, as the opening operation must necessarily be at both ends of the shackle rod.

The device of this application overcomes the above-mentioned objection, as, due to the hinged members of the shackle, the container need be moved only a very short distance, that is, just sufficient to release the rod end from the container engagement, the released rod then being capable of movement upon its hinge to open the shackle to its full extent.

Furthermore, when the two articles to be locked together, as, for instance, the wheels of a baby carriage, are separated from each other by the approximate length of the shackle, an unhinged shackle can not be employed, as the articles can not be inserted through the shackle openings.

My present invention overcomes this difficulty, because of the hinge movement, the

shackle ends can be employed to encompass articles so positioned.

My device, therefore, presents new and valuable features not possessed by my formerly described invention, which will be further evident upon a consideration of my drawings and specification.

In the accompanying drawings, illustrating one form of the device of my invention, similar parts are designated by similar numerals.

Figure 1 is a perspective view of one form of the device of my invention in closed and locked position.

Figure 2 is an enlarged front plan view of Figure 1 with the front plate of the container removed to show the locking mechanism.

Figure 3 is a section through the line 3—3 of Figure 2 with the front plate of the container in place.

Figure 4 is a section through the line 4—4 of Figure 2.

Figure 5 is a perspective view of the container with the front plate removed.

The particular form of the device of my invention, shown in the accompanying drawings, comprises a shackle formed by the rod 10, to which are hingedly attached the bent rods 11 and 12 at 13 and 14 respectively, the ends 15 and 16 of the rods 11 and 12 being spaced from each other.

In order to strengthen the hinge 14, and to protect it from being tampered with, I affix the guard 17 by welding, or otherwise, to the rod 10, the annular member 18 being also affixed to the rod 10. The guard 17 has the fixedly attached pivot rod 14 which extends through an opening in the annular end member 19 of the rod 12 and into an annular bearing within the member 18. By these means, the pivot 14 is protected and enclosed within the guard 17, the latter acting as a stop for the opening and closing movements of the curved rod 12.

A similar guard 20 and pivot 13 are employed in the other hinge movement between the rods 10 and 11.

Slidable along the shackle is a container comprising the member 21 with the surrounding flange 22 and the member 23 with the surrounding flange 24, the flange 22 having the recesses 25, 25 and the flange 24 having the recesses 26, 26 for the passage of

the bars 11 and 12 therethrough. The flange 22 has the recesses 27, 27 and the flange 24 has the recesses 28, 28 for the passage of the bar 10 therethrough.

5 The container member 23 carries the two extended members 29, 29 having a plurality of extended pins 30, 30, which are capable of passing through openings within the container member 21 as a means of holding 16 the two container members together.

The pin 31 of the member 23 is capable of receiving the hole of a key inserted through the keyhole 32 of the member 21, the stop pin 33 limiting the movement of 18 the key.

A locking member 34 has an extended arm 35 slidable through an opening in one member 29 and capable of being inserted into, and withdrawn from, an indent 36 in the 20 rod 10, the other side 37 of the locking member being placed within and slidable through, a recess in the opposite member 29, the movement being limited by the shoulders 38, 38.

The edge face of the locking member 34 25 has an indent 39 so positioned that the revolution of a key around the pin 31 will move the locking member from engagement with the indent 36 of the rod 10, the key, when abutting upon the stop-pin 33, preventing 30 the return movement of the locking member 34.

When the key is revolved into normal position, the spring 40 will return the locking member 34 into engagement with the indent 36 of the rod 10, thus locking the device.

The figures shown in full lines indicate the 40 device in locked position, the locking member 34 being engaged within the indent 36 of the rod 10, thus maintaining the container across the space between the ends of the rods 11 and 12 and preventing it from slidable movement along the shackle. The movement of an inserted key will move the locking member from engagement with the indent 36, allowing the container to be slidably moved along the shackle.

When the container is moved downwardly, 50 the end of the rod 11 will be freed from engagement with the container and can be revolved outwardly upon the hinge 13, as shown in dotted lines in Figure 1, thus allowing it to be placed around an object and revolved to its original position.

55 When the container is moved upwardly, the end of the rod 12 will be freed from engagement with the container and can be revolved outwardly upon the hinge 14, as shown in dotted lines in Figure 2, thus allowing it to be placed around an object and revolved to its original position.

If the key is now removed, the spring 40 60 will bring the member 35 of the locking member 34 in compressed abutment against the rod 10 and, if the container is moved

downwardly, the member 35 will enter the indent 36 of the rod 10, thus locking the container across the space between the ends of the rods 11 and 12 and preventing the removal of the locked objects.

It is evident that, in the form of my device having hinges in the shackle, it is not necessary to move the container so that the space between the container and the end of either of the rod 11 or the rod 12 is sufficient to allow of the introduction of the article to which it is to be locked, as it is sufficient to move it only until the end of one of the rods is free from the container, the hinged movement allowing of the opening of the shackle.

This is a most valuable feature of my device in that it allows of a much shorter shackle than is necessary in an unhinged device, thus being much more economical in construction and more convenient and efficient.

I do not limit myself to the particular size, shape, number or arrangement of parts, as shown and described, as these are given 90 simply as a means for clearly describing my invention.

What I claim is:—

1. In a lock, in combination, a shackle comprising a straight rod, a bent rod 95 hingedly attached to each end thereof, the end portions of the hinged rods being capable of placement in a plane parallel to the straight rods with their extremities spaced from each other, a container capable of slidable movement upon the shackle to bridge the opening between the bent rod extremities and means for locking the container in its bridged position, the container being capable of slidable movement to release each 100 bent rod from retention therein when in unlocked condition.

2. In a lock, in combination, a shackle comprising a straight rod, a bent rod hingedly attached to each end thereof, the end portions of the hinged rods being capable of placement in a plane parallel to the straight rods with their extremities spaced from each other, a container capable of slidable movement upon the shackle to bridge 115 the opening between the bent rod extremities and to release each bent rod from retention therein, an indent within the straight rod, locking means carried by the container capable of insertion within the indent to lock the 120 container from movement when it bridges the opening between the bent rod ends and means whereby a key movement will remove the locking means from the indent allowing a movement to the container.

3. In a lock, in combination, a shackle comprising a straight rod, a bent rod hingedly attached to each end thereof, the end portions of the hinged rods being capable of placement in a plane parallel to the straight 130

rods with their extremities spaced from each other, a container capable of slidable movement upon the shackle to bridge the opening between the bent rod extremities, and to release each bent rod from retention therein, an indent within the straight rod, locking means carried by the container capable of insertion within the indent to lock the container from movement when it bridges the opening between the bent rod ends, means

whereby a key movement will remove the locking means from the indent allowing a movement to the container and spring means whereby the locking means will be returned to its position within the indent when the key movement is released. 15

Signed at New York city, in the county of New York and State of New York, this 24th day of November, 1922.

FRANK P. SHEK.
